UNITED STATES PATENT OFFICE.

WILLIAM D. BUCHTEL, OF PAXTON, NEBRASKA, ASSIGNOR OF ONE-HALF TO WILLIAM E. PAXTON, OF PAXTON, NEBRASKA.

SHOE-LACE FASTENER.

1,138,535.

Specification of Letters Patent.

Patented May 4, 1915.

Application filed December 20, 1913. Serial No. 807,967.

To all whom it may concern:

Be it known that I, WILLIAM D. BUCHTEL, a citizen of the United States, residing at Paxton, in the county of Keith and State of Nebraska, have invented new and useful Improvements in Shoe-Lace Fasteners, of which the following is a specification.

The invention relates to shoe lace fasteners, and more particularly to the class of 10 lacing hooks for shoes, gloves, or the like.

The primary object of the invention is the provision of a lacing hook of this character wherein the shoe lacing can be readily and easily engaged therein and tied in the 15 ordinary manner for the fastening of the shoe on the wearer, the hooks being designed to obviate the catching of the garments thereon.

Another object of the invention is the 20 provision of a shoe lacing hook which is simple in construction, easily manufactured, readily applied in position, and also which will present a smooth surface so that the clothing of a wearer will not become damaged thereby.

With these and other objects in view, the invention consists in the construction, combination and arrangement of parts as will be hereinafter fully described, illustrated in 30 the accompanying drawing, and pointed out in the claim hereunto appended.

In the drawing:—Figure 1 is a fragmentary elevation of a portion of a shoe upper showing the lacing hooks constructed in 35 accordance with the invention. Fig. 2 is a sectional view on the line 2—2 of Fig. 1. Fig. 3 is a fragmentary perspective view of a portion of the shoe upper showing the hook in open position. Fig. 4 is a sectional view taken on line 4—4 of Fig. 5. Fig. 5 is a sectional view taken on line 5—5 of Fig. 4. Fig. 6 is a detail view of the hook element.

Similar reference characters indicate corresponding parts throughout the several views in the drawing.

Referring to the drawing in detail, 5 designates the shoe upper, 6 the lacing, and as these parts may be of the usual or any preferred construction, detailed description is deemed unnecessary. The upper has mount-

ed therein the usual eyelets 7 through which is trained the lacing toward the upper edge of the said upper.

The invention resides in the shoe lacing 55 hook, in this instance two being employed, the same being mounted on the upper near the top free edge thereof. Each shoe lacing hook comprises a base plate 8 formed with corner spurs 9 which are bent at right angles 60 thereto and adapted to be passed through the body of the upper 5 and clenched on the inner side thereof in any desirable manner, the plate 8 being formed with a central elongated opening 10, while on the opposite sides of the latter are out-struck portions 11 providing bearings in which is engaged the cross pivot end 12 of a swinging hook 13 with which is adapted to be engaged the lacing. Secured to and arranged rearwardly of the base plate 8 is a leaf spring 14 which engages with the pivot end 12 of the hook so as to act thereon for sustaining it in open or closed position. The outer or free end of the hook is bent over and under 70 to form a bill 15, having a rounded edge 16 which is directed toward the upper free edge of the upper 5, and this bill 15 is adapted to bear against the shoe upper when the hook 13 is closed, so as to prevent the freeing of 75 the lacing which is engaged with the hook 13 and pulled taut for the tightening of the same when it is desired to fasten the shoe upper to the wearer. When the hook 13 is in closed position the bill 15 thereof is hidden so that a smooth surface is exposed to 80 obviate the catching of the garments of the wearer, thereby avoiding damage to such garments. When the hook is thrown to open position the lacing can be readily drawn out 85 of the bill 15 for the unlacing of the shoe.

From the foregoing it is thought that the construction and manner of use of the device will be clearly understood, and therefore a more extended explanation has been omitted. 90

What is claimed is:—

In a shoe lace fastener, a base plate secured to the upper of the shoe and having an elongated opening therein, bearings rising from said plate at the opposite sides of 100 the opening, a leaf spring interposed between said plate and shoe upper and slightly

spacing the former from the latter, a hook member swingingly mounted in said bearings and operating through the opening in said plate for engagement with said spring whereby the hook is held under tension in either open or closed position, said hook comprising an elongated strip of metal having its free end bent under and rearwardly

of the shank portion of the hook to provide a bill.

In testimony whereof I affix my signature in presence of two witnesses.

WILLIAM D. BUCHTEL.
